UNITED STATES PATENT OFFICE.

THOMAS FORREST SMITH, OF BLACKBURN, ENGLAND.

HUMIDIFIER FOR MOISTENING THE WARP-THREADS OF LOOMS WHEN WEAVING.

No. 856,923.

Specification of Letters Patent.

Patented June 11, 1907.

Application filed January 2, 1906. Serial No. 294,171.

To all whom it may concern:

Be it known that I, THOMAS FORREST SMITH, a subject of the King of Great Britain and Ireland, and a resident of 2 Market, 5 Blackburn, in the county of Lancaster, England, cabinet-maker, have invented certain new and useful Improvements in Humidifiers for Moistening the Warp-Threads of Looms When Weaving, for which I have obtained a patent in Great Britain, No. 11,000, 10 bearing date May 26, 1905, of which the following is a specification.

The object of my invention is to so construct the humidifier that when applied to a loom it will be completely out of the way of the operative and to simplify the method of actuating the humidifier and also to provide means whereby the humidifier can be readily fixed to existing looms or to new looms.

20 The invention comprises an improved frame for supporting the humidifier by means of which the latter can be inserted between the warp beam and the crank shaft of the loom and out of the way of the operative 25 and in so constructing and actuating the humidifier as to cause it to deliver the moisture or moistened air directly on to the warps of the loom.

Referring to the drawings which form a 30 part of this specification:—Figure 1 is a front elevation of a loom fitted with the improved humidifier. Fig. 2 is a sectional end elevation of Fig. 1.

According to this invention the frames 35 1.1 for supporting the water trough 2 of the humidifier are each constructed out of one piece of preferably wrought iron bent in the form of a hoop 3 at its upper end and terminating in two legs which converge toward 40 one another underneath the trough 2 so as to occupy little space and enable the apparatus to be fixed in position between the warp beam 4 and the crank shaft 5 of the loom. The water trough 2 fits inside the hoops 3 and 45 is steadied therein by screws 6.6 which engage with the upper edges of the trough 2 and each end of the latter is provided with bearings for the spindle 8 of the brush 9 which is free to revolve in the aforesaid 50 trough 2. Extending over the brush 9 and secured on the outer surfaces of the hoops 3 by thumb screws or the like is a preferably

sheet metal cover 10. An intervening space or a series of perforations 11.11 is or are left or formed in the sides of the trough 2 and the 55 moistened air is delivered through such space or perforations by the revolving brush 9 and the moisture settles on and damps the warps 12 on or as they leave the warp beam 4. The brush spindle 8 is provided with a pulley 60 13 which is driven by a band 14 from the tapet shaft 15 of the loom.

In applying the invention to new looms the legs 1 of the frames may be turned at an angle and bolted or otherwise secured to one 65 of the cross frames of the loom and in applying the frames to existing looms clamps 16 are provided which can be adjusted vertically on the legs 1 to clamp the latter to any convenient part of the loom framing. In either 70 case the legs may be provided with lengthening or adjusting pieces by means of which the height of the humidifier can be regulated as desired. When the invention is applied to several looms the troughs 2 may be provided with water pipes 17 and fittings by 75 means of which the several troughs may be filled with water simultaneously. The humidifier may advantageously be used in iron foundries public halls and other buildings 80 and if a disinfectant be added to the water in the trough can be employed for disinfecting hospitals consumption homes and the like.

Having now described my invention, what I claim as new and desire to secure by Letters Patent is:—

In a humidifier, the combination, with two supporting legs, each said leg comprising a loop-shaped frame the upper portion of which is provided with a hoop, of a trough 90 supported in the said hoops and having an open top, a revoluble brush journaled in the said trough, and a cover carried by said hoops and arranged over the said trough, two outlet openings being formed, one on each 95 side of the said trough, between its top edges and the bottom edges of the said cover.

In witness whereof I have hereunto set my hand in the presence of two witnesses.

THOMAS FORREST SMITH.

Witnesses:

PERRY HILTON,
FREDK. TALBOT.
